PROCESS AND APPARATUS FOR CRACKING OIL.

Application filed March 23, 1925, Serial No. 17,587. Renewed April 26, 1927.

This invention relates to improvements in cracking heavier hydrocarbon oils, such as gas oil, for the production of lighter hydrocarbon oils, such as gasoline and pressure 5 distillate, therefrom. The invention includes improvements in both method and apparatus.

In cracking heavier hydrocarbon oils in externally heated pressure stills, the heat for 10 the cracking operation is supplied by heating gases, hot products of combustion from a furnace in which fuel is burned, which are applied directly to the heating surfaces of the pressure still, directly to the walls of the 15 still in the case of a shell still and directly to the heating tubes in the case of a tube still. As the cracking operation progresses, the formation in the oil charge of the still of carbon and tar constituents takes place, 20 and, in stills in which the charge is recirculated over the heating surfaces, the extent to which the cracking operation can be carried in a single run is limited by the accumulation 25 of such constituents which tend to settle or separate out on the heating surfaces and to form a layer of so-called "carbon" thereon which interferes with the heat transfer, and, unless periodically removed by 30 cleaning, causes overheating of the walls or tubes of the still. To avoid or minimize the 35 danger of such carbon separation on the heating surfaces, the cracking operation is commonly stopped before the accumulation of heavy tar constituents becomes too great, or 40 the tar is withdrawn and fresh feed supplied to maintain the charge in a sufficiently fluid condition to permit continued operation for a longer time. The danger of such carbon separation and resulting failure of the 45 still walls or tubes is greatest where the heating gases fresh from the furnace and at highest temperature first come in contact with the heating surfaces of the still and where the greatest amount of heating takes place.

According to the present invention, the heating of the pressure still is modified and regulated to protect the heating surfaces of the pressure still itself, to improve the cracking operation, and to increase the capacity and efficiency of the pressure still and heating furnace.

According to the present invention, the heating gases from the furnace are circulated

first over an auxiliary heating coil and are then admixed with hot gases at a lower temperature before being circulated over the heating surfaces of the pressure still proper. Oil is circulated through the auxiliary coil and the auxiliary coil is employed for carrying out a cracking operation, the heat absorbed by the auxiliary coil tempering the heating gases and reducing their temperature. In addition to the tempering action of the heat absorption in the auxiliary coil, 60 hot gases at a lower temperature are admixed with the heating gases after passing over the auxiliary heating coil whereby the heating gases are further cooled and tempered before passing over the heating surfaces of the still proper. This dilution of the heating gases with hot gases of a lower temperature also increases the velocity of the heating gases because of the increase of volume promoting heat transfer and likewise 65 promotes the uniformity of heat absorption on the heating surfaces of the pressure still. The hot tempering gases are advantageously a recycled part of the hot waste heating 70 gases leaving the heating surfaces of the still proper, and where a part of the waste heating gases are so employed at approximately 75 the temperature at which they leave the heating surfaces of the still no heat is lost in the tempering but an increase in both the 80 capacity and efficiency of the still may result. The heating surfaces of the still proper are thus protected in two ways, by the tempering action of the heat absorption 85 in the auxiliary coil and by the tempering 90 due to dilution of the heating gases with hot gases, such as recycled waste heating gases, at a lower temperature.

The oil circulated through the auxiliary heating coil is subjected to the heating gases 95 at highest temperature, that is it is subjected to the most intense heat of the furnace. Substantially tar-free oil is employed for circulation through the auxiliary coil, such for example as reflux, or fresh oil, or 100 admixed reflux and fresh oil. By using such substantially tar free oil in the auxiliary coil, the danger of objectionable carbon deposit on the walls of the auxiliary heating coil is avoided or minimized, even 105 though this coil is subjected to the most intense furnace heat, while at the same time the absorption of heat therein serves to

temper the heating gases. Moreover, according to the present invention, the intense heat to which the oil circulating through the auxiliary coil is subjected is employed in a particularly advantageous manner for cracking reflux and lighter constituents of fresh oil which if directly introduced, or reintroduced, into the pressure still proper might tend to vaporize before cracking absorbing heat in vaporization, which heat, in carrying out the present invention, is usefully applied in the cracking operation.

The auxiliary heating coil is arranged to discharge into the pressure still proper, and, in conjunction with pressure stills provided with reflux towers, the reflux, either with or without admixed fresh oil, is returned to the still proper through the auxiliary coil. The reflux towers may be operated at the same pressure maintained in the pressure still and the reflux, or admixed fresh oil and reflux, circulated through the auxiliary coil by means of gravity or convection circulation or by means of a pump; or the pressure on the vapors escaping from the pressure still may be reduced and the vapors subjected to a refluxing operation at a lower pressure and the reflux, or admixed fresh oil and reflux, pumped through the auxiliary coil and back to the pressure still proper. The present invention is of special value and application in connection with pressure stills provided with reflux towers into which fresh oil is introduced and from which the reflux and admixed fresh oil can be circulated through the auxiliary coil before their introduction into the pressure still proper.

The present invention also is of special value and application in connection with pressure still operations where the vapors from the pressure still are subjected to a high degree of fractionation and the invention provides an advantageous method of handling reflux in such operations. The usual pressure distillates include large amounts of constituents heavier than suitable as components of the desired pressure distillate, for example, in cracking gas oil to produce gasoline the pressure distillate usually includes a considerable amount of constituents of a kerosene character and others even heavier. If the vapors forming the pressure distillate are subjected to a high degree of fractionation, the reflux includes these intermediate constituents, and the method of the present invention is particularly advantageous for handling reflux of this character, the reflux being circulated through the auxiliary coil where it is subjected to the most intense heat and where the reflux, particularly the lighter constituents of the reflux, are subjected to cracking conditions without absorbing heat in vaporization from the main charge of oil in the still proper. One way of subjecting the vapors from the pres-

sure still to a high degree of fractionation is to subject the vapors to a refluxing operation in direct contact with a part of the condensed pressure distillate, or a fraction including constituents of a corresponding character, and the present invention is of special advantage for handling reflux from such operations. In such a combined operation, close control of the character of the pressure distillate is combined with an improved method of treating the lighter constituents of the escaping vapors which are however heavier than suitable as components of the desired pressure distillate with resulting improvement of the entire cracking operation.

Accordingly, in carrying out the present invention, the heating surfaces of the pressure still proper are protected in a dual manner, the heating gases before passing over the heating surfaces of the still proper being tempered first by heat absorption in the auxiliary coil and second by dilution with hot gases of a lower temperature, such as a recycled part of the waste heating gases, while the intense heat absorbed in the auxiliary coil from the heating gases at highest temperature is employed in an advantageous way in the cracking operation carried out in the pressure still system.

This invention will be further described in connection with the accompanying drawings illustrating apparatus embodying the invention and adapted for carrying out the process of the invention, but it will be understood that the invention is illustrated thereby and not limited thereto. The accompanying drawings show, in a diagrammatic and conventional manner, in elevation and partly in section with parts broken away, a tubular pressure still embodying the invention and adapted for the practice of the process of the invention.

While the invention is applicable in connection with cracking stills of different types, yet it is of particular advantage in connection with tubular cracking stills of the character illustrated. This cracking still is of the general construction illustrated in United States Letters Patent No. 1,285,200 granted to the Sinclair Refining Company November 19, 1918 on the application of Edward W. Isom. The pressure still illustrated is made up of the bulk supply tank 1 located away from the heating furnace, the vertical heating tubes 2 arranged in the heating flue of the furnace, and circulating pipes 3, 4 and 5 connecting the lower and upper ends of the vertical tubes, respectively, with the bulk supply tank 1 and a circulating pump 6 for circulating the oil from the bulk supply tank upwardly through the vertical tubes and back to the bulk supply tank.

Arranged above the bulk supply tank is a reflux tower 7 having a series of baffles there-

in and connected with the vapor dome of the bulk supply tank through the vapor line 8. An overflow reflux line 9 leads from the reflux tower back to the bulk supply tank. The 5 vapors from the top of the reflux tower escape through the vapor line 10 to the condenser 11 which is arranged to discharge into the receiver 12 from which uncondensed vapors and gases are drawn off through outlet 13 and liquid condensate through outlet 14. The pressure may be regulated and reduced by means of a regulating valve 15 arranged between the reflux tower and the condenser, or by valves arranged beyond the condenser 10 or receiver. A feed line 26 is provided for feeding fresh oil to the top of the reflux tower 7. Another feed line 27 is provided for feeding cool oil to the bearings of circulating pump 6. A tar draw-off connection 20 for use during the operation of the still is shown at 41 and a tar draw-off for discharging the still is shown at 42.

The furnace construction for heating the tubes 2 comprises a fire-box 16, suitably heated as by gas or oil burners 17, a vertical flue 18 leading upwardly from the fire box to the upper end of the heating flue in which the tubes 2 are arranged, and an outlet flue 19 leading to a stack from the lower end of the heating flue. Baffles are arranged in the heating flue for causing the heating gases to pass back and forth over the vertical tubes in three successive passes. Located above the bridge wall 19' and between the vertical flue 18 and the flue containing the vertical tubes 2 is an auxiliary heating coil 20 having an inlet connecting pipe 21 and an outlet connecting pipe 22, the latter being arranged to discharge into the bulk supply tank through the circulating connection 5. A blower 23 is arranged to withdraw waste heating gases through an outlet 24 located near the exit from the lower end of the heating flue in which the vertical tubes 2 are arranged and return them through inlet 25 to a point in the flue between the auxiliary coil 20 and the upper ends of the vertical tubes 2. The blower illustrated is of the venturi type and may be operated by a steam jet or other suitable means. Two such blowers may be arranged one on each side of the furnace structure.

An auxiliary tank or reservoir 28 is arranged to receive the reflux and admixed fresh oil from the reflux tower 7 through connection 29. This tank or reservoir has a vent pipe 30 connecting with the reflux tower. The tank or reservoir 28 is also connected through the pipes 31 and 32 to the feed line 21 of the auxiliary heating coil. A pump 33 is arranged to pump oil from the reservoir 28 through the auxiliary coil, while the pipe 32, which is provided with valve 34, permits circulation by gravity and by con- 55

60 vention when the pump 33 is not used. A

branch pipe 35 leads from the reservoir 28 to the circulating connection 3 for the discharge of excess oil collecting in the reservoir. Valves 36 and 37 are provided for controlling the flow of oil from the auxiliary 70 reservoir 28. Another feed line 38 connects to the inlet pipe 21 of the auxiliary coil and permits the direct introduction of fresh oil at this point as it is desired. A pipe 39 having a valve 40 therein also connects the inlet 75 of the auxiliary coil to the discharge side of the circulating pump 6. This pipe may be used in starting the still in operation.

In the pressure still illustrated, the auxiliary reservoir or tank 28 is shown as located within the bulk supply tank 1, although it is not in open communication therewith except through the pipe connections. This location of the auxiliary reservoir is not essential but is convenient and enables 85 a tank construction to be used which does not need to withstand high pressure as the pressure inside and out is approximately the same. Where this auxiliary tank or reservoir is located within the bulk supply tank it 90 will be evident that valves, such as valves 36 and 37, should have operating extensions extending through suitable stuffing boxes in the walls of the bulk supply tank. Test cocks (not shown) may be provided for ascertaining the level of the oil in this auxiliary tank or reservoir.

When the still is initially charged, oil may be circulated from the main charge of oil in the still proper through the auxiliary cracking coil, for example, by closing valve 37 and opening valve 36 when the circulating pump 33 will draw oil from the bulk supply tank and circulate it through the auxiliary coil, or the valve 40 may be opened and oil from the discharge side of the circulating pump 6 may be circulated through the auxiliary coil, or fresh oil may be circulated through the auxiliary coil from connection 38.

After the pressure still has been brought to cracking conditions of temperature and pressure, the introduction of fresh oil into the top of the reflux tower through connection 26 is begun. The cracked vapors escaping from the bulk supply tank rise through the reflux tower and come in contact with this fresh oil. By providing a sufficient number of baffles practically all of the feed for the still can be introduced in this way. The reflux and admixed fresh oil from the bottom of the reflux tower collect in the reservoir or tank 28, which, in a still of the type illustrated with a bulk supply tank having a capacity for example of about 10,000 gallons, may have a capacity for example of about 1,000 gallons. From this reservoir the oil is circulated, either by gravity or convection or by pump, through the auxiliary heating coil 20 where it is sub- 125

130

jected to the intense heat of the heating gases substantially as they leave the fire-box 16. The auxiliary coil discharges into the bulk supply tank 1 through the top circulating line 5. The unvaporized portion of the oil so returned forms a part of the still charge and is circulated therewith through the vertical heating tubes 2. The vaporized part of this oil escapes with the vapors from 10 the bulk supply tank to the reflux tower.

It will be evident that the rate of circulation of the oil should be regulated so that a constant supply is provided to the auxiliary coil. By introducing all or practically all of 15 the fresh feed into the top of the reflux tower and bringing it into intimate contact with the vapors therein, a constant supply of reflux and admixed fresh oil is provided.

Should the reservoir 28 become full the additional reflux and feed will collect in the bottom of the reflux tower and will overflow through the connection 9 to the bulk supply tank, or part of the reflux and admixed fresh oil collecting in the reservoir may be 25 discharged through pipe 35 into the circulating line 3. Should there be any deficiency of oil in the reservoir 28 to keep the auxiliary coil full, part of the oil circulating in the still proper may be supplied there- 30 through to pipe 39, or fresh oil may be supplied through connection 38.

The oil circulating through the auxiliary coil is thus made up of reflux constituents and fresh oil constituents and is substantially 35 free of tar constituents. This oil also includes the intermediate constituents refluxed in the reflux tower which are light enough to be vaporized in the pressure still proper but which are heavier than desirable as components of the pressure distillate. These intermediate constituents, if returned directly to the charge of oil in the bulk supply tank, tend to revaporize without further cracking, absorbing heat in a cyclic manner by vaporization in the bulk supply tank and condensation 40 in the reflux tower which is not usefully applied in the cracking operation. By circulating the reflux through the auxiliary coil, these intermediate constituents are positively subjected to a cracking temperature 45 therein. The auxiliary coil is arranged in the heating furnace so that it is subjected to the hottest heating gases substantially at the temperature at which they leave the fire box, 50 and these intermediate constituents, and any lighter constituents of fresh oil circulated through the auxiliary coil, are thus subjected to the most intense cracking conditions maintained in the still system.

55 The absorption of heat from the heating gases in the preliminary coil tempers these gases, and, after passing over the auxiliary coil, the heating gases are further tempered by admixture therewith of part of the waste heating gases returned from near the exit of

the heating flue of the furnace, and the heating gases are then circulated over the heating tubes through which the charge of oil in the still proper is circulated and recirculated. The charge of oil in the still proper, in which 70 tar constituents tend to accumulate, is thus circulated through heating tubes over which heating gases tempered and reduced in temperature, both by the absorption of heat in the auxiliary coil and the recirculation of flue 75 gases, are passed, while the intense furnace heat, before tempering by recirculation of waste heating gases, is employed for heating and cracking the reflux and fresh oil, including the intermediate constituents of the 80 reflux and any lighter constituents of the fresh oil, circulated through the auxiliary heating coil.

Where the oil circulated through the auxiliary heating coil is fresh oil, or admixed fresh oil and reflux, the auxiliary coil can be subjected to such high temperatures and a large amount of heat can be absorbed therein without objectionable carbon deposit on the walls of the tubes of the coil; and after the high temperature furnace gases have been reduced in temperature by passage over the auxiliary coil, and further reduced in temperature by dilution with recirculated waste heating gases, they then 90 pass over the heating tubes of the still proper at a lower temperature and serve to heat these tubes without danger or with materially reduced danger of objectionable overheating. A milder heating and cracking action is thus obtained in the still proper 100 so that the still charge can be cracked to a further extent without danger of objectionable carbon deposit on the tubes while obtaining a heavier residuum from the cracking operation. At the same time, the higher temperature to which the auxiliary cracking coil is subjected also permits the cracking 105 therein of lighter oils, such as kerosene fractions, which are difficult to crack in ordinary pressure stills, and enables the advantageous further treatment of intermediate constituents produced by the pressure still proper and refluxed in the reflux tower within the still system.

115 The heating surfaces of the still proper may be further protected by withdrawing tar laden oil from the main still charge during the progress of the cracking operation, for example through connection 41, and supplying sufficient additional fresh oil to maintain the still charge. The rate of withdrawal of tar laden oil and the rate of supply of fresh oil may be regulated to maintain the tar content of the still charge recirculated through the tubes 2 below saturation during all or the greater part of the run, or the tar may be allowed to accumulate in the recirculating still charge, either 120 during the run or toward the end of the run, 125 130

and the residuum in the still proper reduced to a lower gravity without detriment to the operation.

In cracking gas oil character charging stocks for the production of gasoline, for example, after initially charging the still with gas oil, the gas oil feed introduced during the operation may be supplied to the upper end of the reflux tower through connection 26 and the reflux including the intermediate constituents produced in the still together with the admixed fresh gas oil constituents circulated through the auxiliary coil. For a higher degree of fractionation of the vapors escaping from the pressure still, a part of the pressure distillate, or a fraction of corresponding character, may be supplied to the upper end of the reflux tower through connection 26 in admixture with the gas oil. In this case, the reflux includes, in addition to the heavier intermediate constituents, lighter intermediate constituents which would otherwise escape with the pressure distillate. The reflux tower may also be operated with the introduction only of a light feed, such as a part of the pressure distillate, for effecting close fractionation of the pressure distillate taken off therein, the reflux being circulated through the auxiliary coil, and gas oil charging stock also being supplied to the auxiliary coil through connection 38 or introduced directly into the charge of oil in the still proper, for example through the bearings of the circulating pump by means of connection 27. Kerosene character fractions may also be cracked in the auxiliary coil in such an operation. For example, if the normal pressure distillate includes kerosene as well as gasoline constituents, the pressure distillate bottoms produced on fractionation of the pressure distillate for the desired gasoline fraction may be supplied to the auxiliary coil through connection 38, or kerosene character stocks from other operations may be subjected to cracking treatment in the auxiliary coil. Where the reflux tower is operated with a high degree of fractionation, kerosene character constituents produced in the still are returned to the auxiliary coil with the reflux.

The temperature and pressure employed in carrying out the invention can be varied with different characters of charging stock. Where ordinary gas oil is employed as the principal charge in the pressure still proper, pressures of around 90 to 125 lbs. per sq. in. may be employed, while if lighter oils form the principal part of the charging stock of the pressure still proper, higher pressures may be used, for example, of around 300 to 325 lbs. per sq. in. The pressure maintained in the auxiliary cracking coil may be the same as that in the pressure still or only enough higher to cause the desired circulation; or the auxiliary cracking coil may be

maintained at a considerably higher pressure and the pressure reduced as the cracked oil is discharged therefrom into the pressure still proper.

I claim:

1. An improved method of operating externally heated pressure stills for cracking hydrocarbon oils, which comprises passing heating gases for supplying heat to the cracking operation first over an auxiliary heating coil and then over the heating surfaces of the pressure still proper, admixing hot gases at a lower temperature than the said heating gases with the said heating gases at a point in their passage between the auxiliary heating coil and the heating surfaces of the still proper, and circulating oil through said auxiliary heating coil to the pressure still proper. 70

2. An improved method of operating externally heated pressure stills for cracking hydrocarbon oils, which comprises passing heating gases for supplying heat to the cracking operation first over an auxiliary heating coil and then over the heating surfaces of the pressure still proper, recycling a part of the heating gases which have passed over the heating surfaces of the pressure still proper and admixing them with the heating gases passing from the auxiliary heating coil to the heating surfaces of the pressure still proper, and circulating oil through said auxiliary heating coil to the pressure still proper. 80

3. An improved method of operating externally heated pressure stills for cracking hydrocarbon oils, which comprises passing heating gases for supplying heat to the cracking operation first over an auxiliary heating coil and then over the heating surfaces of the pressure still proper, admixing hot gases at a lower temperature than the said heating gases with the said heating gases at a point in their passage between the auxiliary heating coil and the heating surfaces of the still proper, and circulating substantially tar free oil through the said auxiliary heating coil to the pressure still proper. 100

4. An improved method of operating externally heated pressure stills for cracking hydrocarbon oils, which comprises passing heating gases for supplying heat to the cracking operation first over an auxiliary heating coil and then over the heating surfaces of the pressure still proper, admixing hot gases at a lower temperature than the said heating gases with the said heating gases at a point in their passage between the auxiliary heating coil and the heating surfaces of the still proper, subjecting the vapors from the pressure still proper to a refluxing operation, and circulating reflux therefrom through the said auxiliary heating coil to the pressure still proper. 110

5. An improved method of operating externally heated pressure stills for cracking 120

- hydrocarbon oils, which comprises passing heating gases for supplying heat to the cracking operation first over an auxiliary heating coil and then over the heating surfaces of the pressure still proper, recycling a part of the heating gases which have passed over the heating surfaces of the pressure still proper and admixing them with the heating gases passing from the auxiliary heating coil to the heating surfaces of the still proper, subjecting the vapors from the still proper to a refluxing operation, and circulating reflux therefrom through the said auxiliary heating coil to the pressure still proper.
- 15 6. An improved method of operating externally heated pressure stills for cracking hydrocarbon oils, which comprises passing the heating gases for supplying heat to the cracking operation first over an auxiliary heating coil and then over the heating surfaces of the pressure still proper, admixing hot gases at a lower temperature than the said heating gases with the said heating gases at a point in their passage between the auxiliary heating coil and the heating surfaces of the still proper, subjecting the vapors from the pressure still proper to a refluxing operation in direct contact with fresh oil, and circulating the reflux and fresh oil from the refluxing operation through the said auxiliary heating coil to the pressure still proper.
- 20 7. An improved method of operating externally heated pressure stills for cracking hydrocarbon oils, which comprises passing heating gases for supplying heat to the cracking operation first over an auxiliary heating coil and then over the heating surfaces of the pressure still proper, recycling a part of the heating gases which have passed over the heating surfaces of the pressure still proper and admixing them with the heating gases passing from the auxiliary heating coil to the heating surfaces of the still proper, and circulating substantially tar free oil through said auxiliary heating coil to the pressure still proper.
- 25 8. An improved method of operating externally heated pressure stills for cracking hydrocarbon oils, which comprises passing heating gases for supplying heat to the cracking operation first over an auxiliary heating coil and then over the heating surfaces of the pressure still proper, admixing hot gases at a lower temperature than the said heating gases with the said heating gases at a point in their passage between the auxiliary heating coil and the heating surfaces of the still proper, subjecting the vapors from the pressure still proper to a refluxing operation in direct contact with a fraction corresponding in character to the desired pressure distillate, and circulating reflux therefrom together with additional fresh oil through the said auxiliary heating coil to the pressure still proper.
- 30 9. An improved method of operating externally heated pressure stills for cracking hydrocarbon oils, which comprises passing heating gases for supplying heat to the cracking operation first over an auxiliary heating coil and then over the heating surfaces of the pressure still proper, admixing hot gases at a lower temperature than the said heating gases with the said heating gases at a point in their passage between the auxiliary heating coil and the heating surfaces of the still proper, subjecting the vapors from the pressure still proper to a refluxing operation in direct contact with a fraction corresponding in character to the desired pressure distillate, and circulating the reflux therefrom together with additional fresh oil through the said auxiliary heating coil to the pressure still proper.
- 35 10. An improved method of operating externally heated pressure stills for cracking hydrocarbon oils, which comprises passing heating gases for supplying heat to the cracking operation first over an auxiliary heating coil and then over the heating surfaces of the pressure still proper, admixing hot gases at a lower temperature than the said heating gases with the said heating gases at a point in their passage intermediate the auxiliary heating coil and the heating surfaces of the still proper, and circulating substantially tar free oil through the said auxiliary heating coil.
- 40 11. An improved method of operating externally heated pressure stills for cracking hydrocarbon oils, which comprises passing heating gases for supplying heat to the cracking operation first over an auxiliary heating coil and then over the heating surfaces of the pressure still proper, recycling a part of the heating gases which have passed over the heating surfaces of the pressure still proper and admixing them with the heating gases passing from the auxiliary heating coil to the heating surfaces of the still proper, and circulating substantially tar free oil through the said auxiliary heating coil.
- 45 12. In an externally heated oil cracking pressure still, a heating furnace comprising a heating flue with the heating surfaces of the still arranged therein and having a firebox connected thereto, an auxiliary heating coil arranged to discharge into the still and interposed in the flue between the fire box and the heating surfaces of the still, and means for introducing hot tempering gases into the heating flue between the auxiliary heating coil and the heating surfaces of the still.
- 50 13. In an externally heated oil cracking pressure still, a heating furnace comprising a heating flue with the heating surfaces of the still arranged therein and having a firebox connected thereto, an auxiliary heating coil arranged to discharge into the still and interposed in the flue between the fire box and the heating surfaces of the still.

- coil arranged to discharge into the still and interposed in the flue between the firebox and the heating surfaces of the still, and means for recycling heating gases from the flue beyond the heating surfaces of the still and returning them to the flue between the auxiliary heating coil and the heating surfaces of the still.
14. In externally heated oil cracking pressure stills comprising a bulk supply tank and heating tubes with connections for circulating oil from the bulk supply tank through the heating tubes and back to the bulk supply tank, a heating flue with the heating tubes of the still arranged therein having a firebox connected thereto, an auxiliary heating coil arranged to discharge into the still and interposed in the flue between the firebox and the heating tubes of the still, and means for introducing hot tempering gases into the heating flue between the auxiliary heating coil and the heating tubes of the still.
15. In externally heated oil cracking pressure stills, a reflux tower connected to the still, a heating flue with the heating surfaces of the still arranged therein and having a firebox connected thereto, an auxiliary heat-
- ing coil arranged to discharge into the still and interposed in the flue between the firebox and the heating surfaces of the still, means for introducing hot tempering gases into the heating flue between the auxiliary heating coil and the heating surfaces of the still, and connections for circulating reflux from the reflux tower through the auxiliary heating coil.
16. In externally heated oil cracking pressure stills, a reflux tower connected to the still, means for introducing fresh oil directly into the reflux tower, a heating flue with the heating surfaces of the still arranged therein and having a firebox connected thereto, an auxiliary heating coil arranged to discharge into the still and interposed in the flue between the firebox and the heating surfaces of the still, means for introducing hot tempering gases into the heating flue between the auxiliary heating coil and the heating surfaces of the still, and means for circulating reflux and admixed fresh oil from the reflux tower through the auxiliary heating coil.

In testimony whereof I affix my signature.

EUGENE C. HERTEL.
